FLYING MACHINE

Filed Nov. 18, 1925

Patented Mar. 29, 1927.

UNITED STATES PATENT OFFICE.

ACHILLE SARTINI, OF NEW YORK, N. Y.

FLYING MACHINE.

Application filed November 18, 1925. Serial No. 69,891.

This invention relates to flying machines of the heavier than air type and more particularly refers to an aeroplane of a novel and improved construction adapted to start 5 and to land with practically no run and provided with self balancing means increasing its stability while in flight.

The primary object of this invention is to provide an aeroplane of a novel and improved design, fitted with vertical and horizontal propellers, so mounted that their operation is practically free of reaction due to opposing wing or other surfaces, so that the aeroplane is able to quickly leave the ground 15 in an upwardly inclined direction dependent upon the resultant of the forces exerted by its various propellers.

Another object of this invention is to so construct the wings of the aeroplane that 20 their surfaces will materially assist the operation of the machine when taking off the ground or landing due to the inclination assumed by said surfaces, at such periods.

A further object of the invention is to 25 provide in a machine of the character specified, wings of a novel and improved construction, which will at all times maintain the stability of the machine by automatically counter-balancing the effects of any change 30 that should occur in the conditions of the surrounding medium, whether due to altered speed or to motor trouble, or to air pockets or air currents, or to any cause which may interfere with the proper operation of the 35 machine. With these and other objects in view as will more fully appear as the description proceeds, this invention, furthermore, comprises certain novel constructions and arrangements of parts as will be herein- 40 after described and claimed in the appended claims.

The invention will be best understood by referring to the annexed drawings, in which

Fig. 1 is a plan view of my improved aero- 45 plane in the starting or landing position;

Fig. 2 is a front view in elevation of the same;

Fig. 3 is a side view in elevation of the machine during its movement of ascent;

Fig. 4 is a similar view of the machine in horizontal flight; and

Fig. 5 is a diagrammatic side view in elevation showing the construction and operation of the sectional wings with which the 55 machine is provided.

While the machine forming the object of

this invention may be constructed so as to be capable of vertical ascent, I prefer to merely enable the machine to leave the ground in an inclined direction when start- 60 ing; the inclination of the ascent, however, being much greater than is generally the case with aeroplanes of the ordinary type, where the lifting force is provided entirely by the air striking the inclined surfaces of 65 the wings in a horizontal direction. In my improved machine, part of the lifting force is provided by propellers rotating on substantially vertical axes, and a supplementary lifting action is due to the air impelling 70 against the surfaces of the wings during ascensional flight.

By utilizing the combined action of the vertical and horizontal propellers to produce a rapid ascensional movement of the 75 machine, I am enabled to use vertical propellers of relatively small lifting capacity as compared with those ordinarily used in machines of the helicopter type. One of the great difficulties encountered in the operation of helicopters, or other machines de- 80 signed for the purpose of vertical flight, is the necessity of providing very powerful motors and propellers having a considerable surface. There are definite constructional 85 limitations in the path of the designer which can only be surpassed with difficulty, since increasing power capacity means increase in weight and this in its turn calls for a further increase in power capacity. It is well 90 known that taking the weight of the aeroplane as a basis, a vertical propeller must exert a force more than double the force exerted by a horizontal propeller in order to move the same weight; the weight of the 95 power plant needed therefore, is fully double that of the power plant needed for horizontal flight.

Another factor which usually curtails the ability of a helicopter machine to rise in a 100 vertical direction, is the reaction offered by surfaces pertaining to the machine to the column of air forced down by the propellers, this acting as a brake opposing the ascensional movement. This is, of course, due 105 to defective design, and in some types of machines, arrangements tending to correct this condition have been adopted.

Another characteristic of the present invention lies in a special manner of wing 110 construction at points corresponding to the sphere of action of the vertical propellers,

whereby, while the action of said propellers is not opposed to any extent during the ascensional movement, yet, the full carrying capacity of the wings can be utilized at such points when the machine is in horizontal flight.

Another and important characteristic lies in a novel control of the wing surfaces, causing variations in the incidence of said surfaces to automatically occur when variations in the conditions of the surrounding medium demand it, or when the speed or direction of the machine are changed under the control of the pilot.

15 One or another of the characteristics mentioned may not be sufficient, per se, to produce a machine able to quickly leave the ground and to possess the desired conditions of maximum stability in flight, but the combination of all the characteristics mentioned, produces a machine possessing at one time all the advantages claimed for the helicopter type of machine as well as the advantages of a machine of the ordinary type and possessing other advantageous features which are not found in either type of machine.

20 The drawings illustrate an embodiment of my invention as applied to a biplane, but the same principles may be employed in connection with an aeroplane of the monoplane or triplane type. In said drawings, 10 designates the fuselage or body of the machine which is provided with a horizontal 25 propeller 11 and with two vertical propellers 12, 13 which are symmetrically arranged in relation to the longitudinal axis of the machine and relatively close to the body thereof.

30 40 The propellers are preferably so arranged that the pull of the horizontal propeller and the lifting force due to the combined action of the two vertical propellers pass through the center of gravity of the structure, except in so far as deviations from this rule 45 may be suggested by design and constructional considerations.

45 The plane is provided with an upper wing structure 14 and a lower wing structure 15, each comprising two frames 16, 17 laterally extending from the central structure. The inner portion 18 of each lateral frame, located directly beneath one of the vertical propellers, is constructed Venetian blind fashion, being composed of a plurality of relatively narrow sections 19, which are pivotally mounted transversely of the longitudinal axis of the machine. Owing to this construction, when the machine is at rest, sections 19 just naturally hang down. This permits free and unhampered passage of the downwardly directed column of air displaced by each vertical propeller when the machine is taking off. A horizontal solid 60 wing surface under the vertical propellers

would have the effect of creating a counter-pressure counter-acting the lifting action of the propellers, and this would add considerably to the duty that the propellers would have to perform. On the other hand, the 70 construction described as stated permits the free passage of the air displaced by the propellers and in addition to this permits said air to strike the ground underneath, thus creating a reaction which will actually 75 assist the lifting action of the propellers at the start. This action is also fully utilized owing to the fact that the propellers are laterally displaced with respect to the body 80 of the machine, so that there is no passive resistance offered either by the wings or by the body to their lifting action.

85 During the vertical flight of the machine, the inrushing air impels against the surfaces of sections 19 in a direction from front to rear and forces said sections to remain extended in a substantially horizontal direction to the rear of their pivotal suspensions, forming what practically amounts to a continuous wing surface supporting its share of 90 the weight of the aeroplane while in flight. On the other hand, when said sections 19 are hanging down, owing to their narrow width, they do not oppose any material 95 resistance to the column of air forced rearwardly by the front propeller, so that at the start, the action of both the horizontal and the vertical propellers may be fully utilized.

100 When the machine is started both the horizontal propellers and the vertical propellers are caused to rotate at the same time, so that the combined effect of the horizontal pull and of the lifting force thus exerted 105 is to create upon the machine a resultant pull which is diagonally directed upwardly and forwardly of the starting point, in the general direction indicated by the arrow in Fig. 3. While the machine is thus not lifted in a vertical sense, yet, the direction 110 of its initial travel is sufficiently inclined from the horizontal and the combined force 115 exerted by the propellers is sufficient to cause the machine to leave the ground almost immediately after being started so that no run or only a very short run will be necessary for the machine to leave the ground. This feature is of the utmost importance in permitting as it does, the taking off of the machine from and the landing of 120 the same on relatively restricted areas. Owing to the described construction of wing sections 18, which makes it possible to operate the propellers with full efficiency, it is possible to use motors of less power than 125 would be required under ordinary conditions, therefore, the weight of the machine as a whole is decreased in proportion. Although it is possible to use a single motor for driving all the propellers, if a separate clutch 130

control is provided for each propeller, I prefer to use one motor for the horizontal propeller and another motor for the two vertical propellers; this giving a greater flexibility and less weight, and affording the possibility of saving fuel when the machine is in horizontal flight by operating the horizontal propeller only. Furthermore, by using two motors instead of one, a more uniform distribution of weight is obtained and a lighter supporting structure may be employed.

The easy operation of the machine, both during the ascent and during its normal flight is further enhanced by the novel construction of the wings and more especially by the form of automatic balance control provided therefor. The main wing structure extends from the inner portion 18 of each frame to the tip portions or ailerons 20, 21. Said main wing structures designated by numerals 22, 23, are also composed of a number of sections 24, 25, 26, pivotally mounted to the frame transversely of the longitudinal axis of the machine, and depending from said frame. Said sections preferably three, for the entire depth of the wing are of an increasing width from front to rear, the rear section 26 being wider than the intermediate section 25, which is in its turn wider than the front section 24. Said sections are connected to each other by articulated connections such as 27, 28, associating one section to another and causing angular motion of all the sections around their respective pivots to take place simultaneously.

The result is an articulated structure which may be opened to the position shown in Figs. 3 and 5, where the wing sections are downwardly inclined towards the rear of the machine, or closed to the position shown in Fig. 4 also shown in dot-and-dash lines in Fig. 5, where the various sections are overlapping each other in a substantially horizontal direction, forming a supporting plane of the ordinary type.

When the wing sections are in the position of Fig. 4, the ascensional movement of the machine may take place with little resistance on the part of said wings; in fact, the wings are so designed that their sections are inclined closer to the vertical than the direction of the diagonal travel of the machine, so that the inrushing air strikes the wing sections at an angle which causes the impelling force to produce an upwardly directing resultant, which may be comparable to the lifting force exerted by the wings of an aeroplane of an ordinary type, due to their incidence and which materially assists the lifting action of the propellers. In order to do this, it is, of course, necessary that retaining means be provided opposing the rearward swinging motions of the wing sec-

tions when thus impelled by the air and this retaining force is provided by elastic tension members such as 29 attached at one end at 30 to the frame and at the other end to the front section 24 at 31. Said elastic members are each caused to pass over a forked member 32 which is pivotally mounted transversely of the frame and which may as is the case in the design shown, be co-pivotal or integral with the front wing section 24. 70 The effect of said forked member is to cause an elongation of the elastic members when the wing sections are forced rearwardly to their horizontal position shown in dot-and-dash lines in Fig. 5 and therefore, the forcing back of the wing sections to this position results in an increased tension of the elastic members. While the elastic members are shown attached at 31 to the front wing section 24 only, it is obvious that the same 75 may be extended also to the intermediate and rear wing sections as shown by dot-and-dash lines at 33.

Owing to the construction described, the wing sections normally tend to remain in 80 their open position shown in Figs. 3 and 5, and will only vary slightly from said position during the diagonal upward travel of the machine due to the resistance offered by their surfaces to the impelling air. However, as soon as the desired altitude has been 85 reached, the vertical propellers may be slowed down or cut off altogether, and the machine will start to travel in a horizontal direction due to the action of the horizontal 90 propeller. The forces exerted by the air against the wing surfaces is now much stronger and will cause the said surfaces to assume the horizontal position shown in Fig. 4 and also shown in dot-and-dash lines 95 in Fig. 5, where the various sections overlap one another, forming the equivalent of a continuous surface supporting the weight of the aeroplane in the ordinary manner. However, the elastic tension members are now 100 subjected to an increased tension and will act immediately towards increasing the angle 105 of incidence of the wing sections if, for any reason, the force exerted by the impelling air should diminish. This might be due 110 to any one of a number of causes; it may be due to the deliberate slowing down of the motor by the pilot for the purpose of effecting the descent of the machine, or it may be due to the stalling of the motor or to diminished wind pressure, or to air pockets 115 suddenly encountered by the machine while in flight, or to any other cause. When the causes, thus altering the buoyancy or supporting action of the surrounding medium 120 cannot be foreseen, as is the case with air pockets or mishaps to the motor, a dangerous condition is usually created where the pilot must act immediately in order to prevent overturning or spinning of his machine. 125 130

In the present case, the element of danger due to these various sources is practically removed, because the moment the buoyancy of the air is lessened the elastic tension members will act to counter-balance the force exerted by the air against the wing surfaces and will therefore, instantly increase the angle of incidence of the said wing surfaces. This, in its turn, will result in an increase in the resistance offered by said surfaces to the impelling air and therefore, an increase in the lifting force due to the vertical component of said resistance. The inclination assumed by the wing surfaces will thus automatically counteract any tendency of the aeroplane to descend or to capsize.

The elastic tension members are preferably made of a good grade of rubber and may be made in the form of rubber cords having a diameter and a strength sufficient to stand the stresses imposed upon them. While the drawings show these tension members attached only to the extreme ends of the wing sections, it is obvious that intermediate tension members may be employed so that the load may be distributed more uniformly between a plurality of tension members of a relatively small diameter.

The tip portions or ailerons 20, 21, are each composed of a frame 33, 34, having preferably a plurality of sections such as 35, 36, 37, which are also firmly mounted on said frame transversely of the longitudinal axis of the machine as explained in connection with wing sections 24, 25, 26. Sections 35, 36, 37 are also of an increasing width from front to rear and are connected to each other by articulated connections in the manner explained in connection with wing sections 24, 25, 26. Their frames 33, 34 may be controlled by the pilot in the usual manner for the purpose of varying the inclination of said frames in relation to the horizontal; this is needed for instance when taking a turn, in which case the angular incidence of the inner tip is increased while the angular incidence of the outer tip is increased. But the sections themselves, 35, 36, 37 are automatically controlled by elastic tension members in the same manner as explained in connection with sections 24, 25, 26. In aeroplanes of ordinary design, the pilot must be very careful when taking a turn to re-balance the plane as soon as the turn has been taken. In frequent instances, where the pilot, due to inexperience or inadvertence, has failed to reset the inner tip at the proper angle, serious accidents have taken place, causing the death of the pilot. This is due to the rapid spiral gliding movement of the machine which may take place causing the machine to spin and capsize.

The aeroplane forming the object of the present invention is controlled in the ordinary manner, when sudden changes of direc-

tion have to be effected; but any mishap due to the failure of the pilot to properly perform the various maneuvers required will be positively prevented by the self-balancing feature described, because the lower resistance offered by the air against the surfaces of the inner tip due to its lower speed immediately results in an increase of the angle of incidence of its sections due to the action of the elastic tension members. This action is also supplemented by a similar action of the sections constituting the inner main wing structure; and it is even possible if a simplified construction should be desired to make the aileron sections with a solid plane surface and to rely entirely upon the main wing structures for the automatic balancing of the machine.

The lower wing structure substantially corresponds in its construction and arrangement to the upper wing structure, although the relative dimensions and arrangement of the various wing surfaces are subject to various changes according to requirements.

The drawings are therefore to be considered as intended for illustrative purposes only and not in a limiting sense.

The described pivotal arrangement of the wing sections also permits of exerting a braking action impeding the horizontal progress of the machine when the driving propeller is slowed down for the purpose of effecting a landing; therefore, also in this case, it is possible to land with practically no run or with a very small run so that no large landing field is required.

The necessity of providing as flexible a method of control of the various movements of the machine as possible, further emphasizes the advantage of having separate motors for the horizontal or driving propeller and the vertical or lifting propellers. Such an arrangement permits of operating only one set of propellers at one time or of operating both sets at the same time and also permits speed variations in one of the set of propellers independently of the other, without the necessity of using any complicated speed change mechanism. The advantages of such an arrangement are obvious, for instance, when taking off, it is usually desirable to run both sets of propellers at a maximum speed; in horizontal flight it may be desirable to cut off the landing propellers entirely and to run the driving propeller at maximum speed, or else it may be preferable in certain cases to run the lifting propellers at a low speed and the driving propeller at a high speed. When landings are effected, on the other hand, it may be preferable to merely decrease the speed of the driving propeller or to both decrease the speed of the driving propeller and to run the lifting propellers at a moderate speed, or else it might even be desirable when the aeroplane

already possesses a high horizontal speed, to cut off entirely the driving propeller and to run the lifting propellers at a high speed. In this case, the lifting propellers will counterbalance a part of the weight of the machine which is caused to descend in a diagonal direction owing partly to its momentum and partly to the balance of its weight, which is in excess of the lifting power of the lifting propellers. These various combinations would hardly be possible if the same motor were employed to drive both the driving and the lifting propellers.

At various points in this specification, the term vertical propellers has been employed to indicate propellers rotating around vertical axes on a horizontal plane and the term horizontal propeller has been used to indicate a propeller rotating around a horizontal axis in a vertical plane. However, both terms are intended to be rather generic in their meaning because the vertical propellers which will be referred to in the claims as lifting propellers or vertical propulsion means may in practice be caused to rotate on axes somewhat inclined from the vertical if desired; and in a similar manner the horizontal propeller, referred to in the claims as a driving propeller or horizontal propulsion means, may be caused to rotate around an axis somewhat at an angle to the horizontal. It is also obvious that more than one driving propeller and less or more than two lifting propellers may be used and that all the driving propellers or all the lifting propellers may be driven by the same or by separate motors, respectively.

In view of these remarks, I reserve myself the right to carry my invention into practice in ways different from that shown, such as may enter, fairly, into the scope of the appended claims.

I claim:

1. In a flying machine, the combination with a body, of a supporting wing structure therefor, said wing structure comprising a frame and a plurality of plane sections in front to rear serial arrangement at each side of said body, pivotally mounted on said frame transversely of the longitudinal axis of said body, and elastic retaining members for said sections tending to maintain said sections in a downwardly directed position from their respective pivotal points of attachment.

2. In a flying machine, the combination with a body, of a wing structure comprising a frame and a plurality of supporting plane sections in front to rear serial arrangement at each side of said body, pivotally mounted on said frame transversely of the longitudinal axis of said body, said plane sections being adapted to form a continuous supporting surface when rearwardly directed from their points of pivotal attachment, in a

substantially horizontal direction, and elastic connections, between said plane sections and said frame tending to maintain said plane sections in a downwardly directed position from their point of attachment. 70

3. In a flying machine, the combination with a body and with a wing structure therefor, of wing tip sections each comprising a frame having a variable angle of incidence controllable by the operator, plane sections 75 pivotally mounted on said frame transversely of the longitudinal axis of said body, and elastic connections between said frame and said plane sections tending to maintain said sections in a position downwardly directed 80 from their points of pivotal attachment.

4. In a flying machine, the combination with a body, of a wing structure comprising a frame, wing tip sections movably mounted on said frame, and a plurality of supporting 85 plane sections, pivotally mounted on said frame transversely of the longitudinal axis of said body, and elastic connections between the said plane sections and said frame, tending to maintain said plane sections in a position 90 downwardly directed from their points of pivotal attachment.

5. In a flying machine, the combination with a body, of a wing structure comprising 95 a stationary frame, wing tip sections each comprising a frame movable in relation to said stationary frame, supporting plane surfaces pivotally mounted on said stationary and movable frames transversely of the longitudinal axis of said body and elastic 100 connecting members between said plane sections and their relative supporting frames.

6. In a flying machine, the combination with a body, and means adapted to generate an upward diagonally directed lifting and 105 propelling force therefor, of a wing structure comprising a stationary frame, supporting plane surfaces, pivotally mounted on and depending from said frame, normally disposed at a slight angle to the direction of 110 said force causing the air impelling against said surfaces to assist the lifting action of said force, and elastic members connecting said plane surfaces to said frame.

7. In a flying machine, the combination with a body of horizontal propulsion means, vertical propulsion means, a supporting wing structure for said body, said structure comprising supporting plane sections underneath said vertical propulsion means composed of a plurality of relatively narrow sections, pivotally mounted transversely of the longitudinal axis of said body, said sections being adapted to be normally directed downwardly from their points of pivotal attachment and being adapted to swing rearwardly of said vertical position when a longitudinal rearwardly directed air pressure is exerted against their surfaces and comprising additional plane sections pivot-

ally mounted transversely of the longitudinal axis of said body, and means for automatically governing the angle of incidence of said last mentioned plane section 5 according to the reaction of the air against said surfaces during the travel of the machine.

8. In a flying machine, the combination with a body, of a driving propeller arranged 10 centrally of said body, two lifting propellers arranged symmetrically to the central axis thereof, a supporting wing structure for said body, comprising plane sections underneath said lifting propellers, composed of a plurality of relatively narrow sections pivotally mounted transversely of the longitudinal axis of said body, said sections being adapted to be normally directed downwardly from their points of pivotal attachment and being 15 adapted to swing rearwardly of said vertical position when a longitudinal rearwardly directed air pressure is exerted against their surfaces, and comprising additional plane sections pivotally mounted transversely of the longitudinal axis of said body, and elastic retaining members for said last mentioned sections, tending to maintain said sections in a downwardly directed position from their respective pivotal points of 20 attachment.

9. In a flying machine, the combination with a body, of a driving propeller arranged centrally of said body, two lifting propellers arranged symmetrically to the central axis 25 thereof, a wing structure comprising a stationary frame, plane sections underneath said lifting propellers, composed of a plurality of relatively narrow sections pivotally mounted on said frame, transversely of the longitudinal axis of said body, said sections being adapted to be normally directed downwardly from their points of pivotal attachment, a plurality of supporting plane sections pivotally mounted on said frame trans- 30 versely of the longitudinal axis of said body, all the said mentioned plane sections being adapted to form a continuous supporting surface when rearwardly directed from their points of pivotal attachment in a substantially horizontal direction, and elastic connections between said last mentioned plane sections and said frame, tending to maintain said plane sections in a downwardly directed 35 position from their point of attachment.

10. In a flying machine, the combination with a body, of a driving propeller arranged centrally of said body, two lifting propellers arranged symmetrically to the central axis thereof, a wing structure for said body 40 comprising a stationary frame, plane sections underneath said lifting propellers composed of a plurality of longitudinal narrow sections, pivotally mounted transversely of the longitudinal axis of said body, said sections being adapted to be normally directed

downwardly from their points of pivotal attachment and being adapted to swing rearwardly of said vertical position, when a longitudinal rearwardly directed air pressure is exerted against their surfaces, wing tip sections each comprising a frame having a variable angle of incidence in relation to said stationary frame, plane sections pivotally mounted on said wing tip frames transversely of the longitudinal axis of said body 45 and elastic connections between said wing tip frames and said plane sections, tending to maintain said sections in a position downwardly directed from their points of pivotal attachment.

11. In a flying machine, the combination with a body, of a driving propeller arranged centrally of said body, two lifting propellers arranged symmetrically to the central axis thereof, a wing structure for said body comprising a stationary frame, plane sections underneath said lifting propellers, composed of a plurality of relatively narrow sections, pivotally mounted transversely of the longitudinal axis of said body, said sections being adapted to be normally directed downwardly from their points of pivotal attachment and being adapted to swing rearwardly of said vertical position, when a longitudinal rearwardly directed air 50 pressure is exerted against their surfaces, wing tip sections movably mounted on said frame, a plurality of additional supporting plane sections, pivotally mounted on said frame, transversely of the longitudinal axis 55 of said body, and elastic connections between said last mentioned plane sections and said frame tending to maintain said sections in a position downwardly directed from their points of pivotal attachment.

12. In a flying machine, the combination with a body, of a driving propeller arranged centrally of said body, two lifting propellers arranged symmetrically to the central axis thereof, a wing structure for said body, comprising a stationary frame, wing tip sections, each comprising a frame movable in relation to said stationary frame, supporting plane surfaces pivotally mounted on said stationary and movable frames, transversely of the longitudinal axis of said body and elastic connecting members between said plane sections and their relative supporting frames.

13. In a flying machine, the combination with a body, of a driving propeller arranged centrally of said body, two lifting propellers arranged symmetrically to the central axis thereof, a wing structure for said body comprising a stationary frame, plane sections underneath said lifting propellers, composed of a plurality of relatively narrow sections, pivotally mounted transversely of the longitudinal axis of said body, said sections being adapted to be normally directed down-

wardly from their points of pivotal attachment and being adapted to swing rearwardly of said vertical position, when a longitudinal rearwardly directed air pressure is exerted against their surfaces, wing tip sections movably mounted on said frame, a plurality of additional supporting plane sections, pivotally mounted on said frame, transversely of the longitudinal axis of said body, plane sections pivotally mounted on said movable frames transversely of the longitudinal axis of said body, and elastic connections between said second and last mentioned plane sections and their relative supporting frames.

14. In a flying machine, the combination with a body, of a supporting wing structure therefor, said wing structure comprising a frame and a plurality of plane sections in front to rear serial arrangement at each side of said body pivotally mounted on said frame transversely of the longitudinal axis

of said body, each section having a greater width than the adjoining section at the front thereof, and elastic means for retaining said sections in a downwardly inclined position. 25

15. In a flying machine, the combination with a body, and means adapted to generate an upward diagonally directed lifting and propelling force therefor, of a wing structure comprising a frame and a plurality of plane sections in front to rear serial arrangement at each side of said body, pivotally mounted on said frame transversely of the longitudinal axis of said body, each section having a greater width than the adjoining section at the front thereof, said sections being normally displaced at a slight angle to the direction of said force, causing the air impelling against the surfaces of said sections to assist said force in lifting said machine. 30 35 40
